UNITED STATES PATENT OFFICE.

MADS M. LARSEN, OF COLTON, CALIFORNIA.

SASH PULLEY.

Application filed September 25, 1923. Serial No. 664,702.

To all whom it may concern:

Be it known that I, MADS M. LARSEN, a citizen of the United States, residing at Colton, California, in the county of San Bernardino and State of California, have invented new and useful Improvements in Sash Pulleys, of which the following is a specification.

This invention relates to builders' hardware and more particularly to sash pulleys.

It is one of the broad objects of the present invention to provide a sash pulley device constructed as a unitary structure which is adapted to be readily inserted into a primary part, such as a window casing stile, with a minimum amount of labor and by a simple operation of cutting the sash to receive the pulley. Further, an object is to provide a sash pulley device which need not necessarily be fastened by any extraneous means to the part in which it is mounted.

Another object is to provide a sash pulley which is of such construction that the liability of the sash cord from jumping is practically eliminated, and further, an object is to provide a sash pulley device having means to facilitate the introduction of the sash cord.

Other objects and advantages will be made manifest in the following specification of an embodiment of the invention illustrated in the accompanying drawings, wherein:

Figure 1 is a perspective of the detached device and showing a pulley cord rove therein.

Fig. 2 is a horizontal section and plan showing the device installed.

Fig. 3 is a longitudinal section through the parts of the device.

Fig. 4 is a section on line 4—4 of Figure 2.

The form of the device as shown includes a tubular shell or casing 2 which is here shown as substantially cylindrical in form, though it is not necessarily limited to such

form. One end of the shell 2 is provided with an outwardly extending shoulder or stop means in the form of a flange 2^a. Within the shell 2 are provided transversely extending shafts or axles 3, which may be

suitably mounted in the opposite side portions of the shell as clearly shown in Figure 4, and if desired may be rigidly fixed as by soldering or welding, indicated at 4, and thus preventing endwise movement of the axles 3. Mounted on each axle is a guide

roller or pulley 5, these rollers being shown

as disposed adjacent the ends of the shell 2 so as to form suitable guide means for the sash rope R connected in the usual manner to a sash weight and to a sash.

A feature of the invention consists of means to facilitate the threading of the sash rope R through the shell 2 and across common sides of the spaced guide rollers 5. Such means is indicated as a transversely extending guide portion 6 which, for economy of construction and for simplicity, may be formed by punching down and into the shell 3 a portion of the shell between the axles 3—3. Thus the transverse part 6 prevents the end of the rope R being pushed through the shell from passing down between the two pulleys and thus this part 6 guides the rope through the shell.

When installing the present sash pulley device it is only necessary to drill a round hole with an auger in the window frame part F of a size substantially corresponding to the size of the given shell 2, and this latter is then driven into the hole H in the frame 80 and thus retained firmly in place by pressure of the surfaces of the shell and hole. Means are provided for preventing the rotation of the shell, and is shown as consisting of a longitudinally extending rib or fin 7 on the 85 outside of the shell. This fin preferably has an inclined edge 7^a so that it will readily cut into the wood of the frame when driven in.

Obviously, if desired, a nail, screw or other 90 retaining means 10 may be driven through the stop shoulder or flange 2^a into the window frame.

From the above it will be seen that I have provided a sash pulley device of utmost 95 simplicity and of substantial formation and few parts, and have provided a device which may be quickly mounted in a hole which may be cut by a rapid and very inexpensive method.

Further embodiments, modifications and variations may be resorted to within the principle of the invention.

What is claimed is:

1. A sash pulley device comprising a shell 105 having mounted in its interior a set of guide pulleys for a sash cord, and a guide formed integral with and extending transversely across the interior of the shell and for the purpose of preventing the sash rope being 110 threaded through the shell from passing between the said pulleys.

2. A sash pulley device comprising a shell having mounted in its interior a set of guide pulleys for a sash cord, and a guide extending transversely across the interior of the shell and for the purpose of preventing the sash rope being threaded through the shell from passing between the said pulleys, said guide consisting of an inwardly struck portion of the shell wall.
3. A sash pulley device comprising a shell

having mounted upon the interior thereof a set of guide pulleys for a sash cord, and a guide for preventing the sash cord being threaded through the shell from passing between said pulleys, said guide consisting of a portion of the top of the shell being pressed downwardly between said pulleys. 15

In testimony whereof I have signed my name to this specification.

MADS M. LARSEN.
